UNITED STATES PATENT OFFICE.

JAMES J. WOOD, OF BROOKLYN, NEW YORK.

INCANDESCENT-LAMP SOCKET.

SPECIFICATION forming part of Letters Patent No. 431,681, dated July 8, 1890.

Application filed December 14, 1887. Serial No. 257,868. (No model.)

To all whom it may concern:

Be it known that I, JAMES J. WOOD, of Brooklyn, Kings county, New York, have invented certain new and useful Improvements 5 in Electric-Lamp Holders, of which the following is a specification.

My invention relates more especially to holders for incandescent lamps used in series on constant-current or automatically-governed dynamos; and my improvements lie chiefly in safety devices to maintain the current to the other lamps in case of the breakage of any one lamp in the series, or to insure the lighting of a second lamp in case its twin 15 becomes broken.

My invention therefore consists, partly, in contact devices operated by the insertion of the lamp in the socket of the holder or by its removal therefrom and carrying a small disruptive cut-out device and in the special form of this cut-out device; also, in a small hand-switch to make a quick break between the terminals after the lamp is put in circuit to prevent arcing; also, in the combination 25 of two lamps and a disruptive cut-out between them, with paths between the cut-out and the two lamps so arranged that in case either lamp is broken the current is established to the other by disruption through the 30 cut-out.

My invention therefore consists, mainly, in the features above outlined, as well as in the particular construction and combination of parts, as hereinafter fully set forth and claimed.

In the drawings annexed, Figure 1 is a sectional elevation of my improved lamp-holder. Fig. 2 is a similar section, but at right angles, or on line $y-y$ of Fig. 1. Fig. 3 is a cross-section or plan on line $z-z$ of Figs. 1 and 2. Fig. 4 is a sectional detail of the cut-out, and Fig. 5 a detail of the hand-switch. Fig. 6 is a fragmentary external view of the holder. Fig. 7 is a diagram showing the cut-out applied to 45 twin lamps, designed to maintain one in case the other breaks. Fig. 8 is a cross-section or plan of Figs. 1 and 2 below the line $x-x$, and Fig. 9 is an inverted plan on $o-o$.

Referring to the drawings, more especially 50 Figs. 1, 2, and 6, it may be seen that in general external form and appearance the holder is similar to what is known as the "Edison

lamp-holder," and is formed with a screw-socket a to receive an Edison lamp.

b is the attaching base or head of the holder, 55 which has the usual screw-neck b' to screw onto the fixture, and also the cupped rim c , which is secured to the external shell or casing d and also to an internal disk or plate e , of slate or other insulating material, to which 60 the internal operative parts of the holder are attached and which forms a fire-proof insulating-base therefor. The slate disk e abuts on one side against two lugs or projections $g-g$, cast on and depending from the head b , (see 65 Figs. 1 and 2,) and is secured to said lugs by the screws $f-f$. (Seen in Figs. 3 and 9.) Now the screw-socket a at the mouth of the holder, which is, as usual, a short section of sheet-metal tube, in which a coarse round screw- 70 thread is spun, is secured metallically to a cast-metal ring h , (seen best in Figs. 1, 2, and 9,) which ring has two prongs or legs $k-k'$ projecting therefrom, which are fastened by screws to the slate disk e , as will be understood from 75 Figs. 2, 3, 9, and 8. Now, at about right angles to the legs $k-k'$ of the ring h a small metallic bracket l is fastened to the slate disk, which, curving downwardly and inwardly, projects centrally between the legs $k-k'$ and terminates in a small vertical bearing l' , which 80 is in line with the center of the slate disk e and the metal ring h , as fully shown in Figs. 1, 2, and 9. In this bearing l' is fitted a small vertical spindle m , the lower end of which 85 terminates with a slotted head m' , which projects down through the center of the ring h over the center of the screw-socket a , and hence in the path of the screw-neck of the lamp when inserted therein, as will be evident from Figs. 1 and 2. (See also Fig. 7.) The upper end of the spindle is secured to a small circular metallic disk, platform, or turn-table n , the under side of which normally rests on a metallic tongue or prong o , projecting 90 from the leg k of the ring h , as best shown in Fig. 2. Now, one of the circuit-wires + connects to the leg k' , as shown by full and dotted lines in Fig. 2, and is hence in metallic connection with the prong o , while the other 95 wire — connects to the bracket l , as seen in Figs. 1 and 2, and is hence in connection with the table n , so that therefore when the table n is in contact with the prong o , as seen in Fig. 100

2, which is always the case when the lamp is removed from the socket *a*, the circuit will therefore be closed through the contacts *n o*, and the current thus maintained to the other 5 lamps, which are in their holders and in the same circuit. It will be understood, however, referring to Figs. 1 and 2, that when the lamp is inserted in the holder the end of the screw-neck on the lamp in being screwed home in the 10 socket *a* will contact with the head *m'* of the spindle *m*, and thus ultimately lift the table *n* off the contact-prong *o*, thus breaking the short circuit between *n* and *o* and at the same time putting the lamp itself in circuit, for of 15 course the socket *a* and head *m'* form the two terminals of the circuit in the holder, which thus contact with the two terminals on the screw-neck of the lamp, and thereby put the lamp in circuit. It will be noted, however, 20 that if reliance were placed solely on the breaking of the short circuit at *n o* to put the lamp in circuit through the terminals *a m'*, the resistance of the lamp being high, while the separation of *n o* is made comparatively 25 slowly by the screwing in of the lamp, an arc might in some cases form at the separated contacts *n o*, instead of the current flowing through the lamp. I therefore provide a small hand-switch, which will keep the short 30 circuit closed until the lamp is put in and the contacts *o n* are separated and will then break the short circuit instantly, so as to put the lamp in circuit without forming an arc at *n o*. This switch is shown at *p* in Figs. 1, 2, 35 and 3, and consists of a small metallic bar pivoted at the middle of the slate disk *e* on the stud *p'* (see Figs. 2 and 3) and extends diametrically across the disk, as shown, with its operating end provided with a non-con- 40 ducting tip projecting through a notch *d'* in the casing *d*. (See Figs. 1, 6, and 3.) A coiled spring *q* is fixed at one end to the switch and at the other to a pin *q'*, fixed on the disk *e*, as seen in Fig. 3, and when the switch is swung 45 around into its "closed" position against the stress of the spring it enters at each end in the grasp of contact clasps *r r'*, as shown best in Figs. 3 and 5, which clasps are fixed on top of the slate disk and are connected with 50 the opposite circuit-terminals of the holder—that is, one clasp is connected with the leg *k'* of the ring *h*, while the other clasp is connected with the bracket *l*, as shown by dotted lines in Fig. 3, so that when the switch is 55 closed it forms a short circuit between the circuit-wires $+$ $-$; hence when the switch is thus closed the lamp may be freely screwed into the socket to put its contact-terminals into contact with the terminals *a m'* and to sepa- 60 rate the contacts *n o*, and no current can now flow through the lamp or across the contacts *n o*. It will be noted that when the switch is thus swung around into its closed position it will move in the circumferential slot *d'* in the 65 casing *d*, (see Figs. 6 and 3,) and will be finally sprung up into the notch *d'* at the end of the slot, as seen in Fig. 6, which will thus

hold the switch closed against the tendency of the spring *q* to open the same, so that therefore when the switch is depressed out of the notch in line with the slot the spring will cause it to fly instantly open, thus instantaneously breaking the circuit between the clasps *r r'*, and thus putting the lamp in circuit. 70

When it is desired to extinguish the lamp, it is only necessary to move back the switch to its closed position, the switch thus serving as the key to light and extinguish the lamps without ever actually breaking the serial circuit. If, on the other hand, the lamp should be removed from the socket while the switch is open, the table *n* will seat on the contact *o*, as seen in Fig. 2, before the terminals *a m'* break contact with the retreating lamp, thus closing the circuit and keeping it intact with the other lamps in the series, and thereby acting as a safety device or safety-switch, which prevents any injury to the circuit or extinguishment of the other lamps 80 in case it has been forgotten to close the hand-switch *p* before removing the lamp; hence by these means the lamp may be removed, whether the switch is open or closed, without any injury. Another contingency, 90 however, still remains to be provided for—that is, if a lamp in any of the holders should become broken while in use it would be necessary to provide a cut-out or short circuit for the current to the other lamps in 100 the series. This I accomplish by providing the top of the table *n* with a thin disk or washer *s*, of waxed paper or similar disruptive insulating-layer, which, as shown best in Fig. 4, is preferably held in place by 105 a central screw *s'* and an insulating-washer *t*. A contact-spring *u*, fixed to and projecting from the leg *k'* of the ring *h*, bears at its tip upon the disruptive disk *s*, as shown in Figs. 2, 8, and 9. It will therefore be seen that 110 when the current takes its normal path through the intact lamp it cannot pass through the disruptive insulator *s* to make a short circuit between the spring *u* and table *n*, which are of course of opposite polarities. If, however, the lamp should become broken, the current will instantly jump through the thin insulator with a disruptive action, burning or puncturing a hole through the same, which 115 will permit the spring *u* to contact with the table *n*, and thus make a short circuit, which will conduct the current to the other lamps, and thus keep the serial circuit intact. After 120 the broken lamp is removed a new one can be inserted, and by means of a screw-driver the slotted head *m'* of the spindle *m* may be turned so as to rotate the table *n* and bring an imperforate part of the insulator *s* under the spring *u* to set the disruptive cut-out ready for action if again required. 125

The fixed contact *o* and movable contact *n*, operated by the insertion and removal of the lamp, I may call the "safety-switch" or "cut-out," while the contacts *u n*, separated by the 130

- thin disruptible insulator s , I may call the "disruptive cut-out," and these two features may be combined and arranged in various ways in connection with one or more electric lamps without departing from my invention. For example, one way of arranging them in connection with a set of twin safety-lamps is shown in Fig. 7, in which case it is designed that only one lamp of the pair can be lighted at once, and if one of the two should break the other will become automatically lighted. In this case v indicates the hanger or holder, having the screw-sockets a , in the throats of which are mounted the movable contact-pushes m' , corresponding to the part m' in Fig. 2. These pushes m' , however, instead of acting on the turn-table n , holding the disruptible insulator, act on contact-springs n' , which are respectively fixed to the terminals $+$ $-$, and rest at the free ends on the conducting-plate v' ; hence when neither of the lamps is in its socket the springs $n' n'$ will rest on the plate v' and form a short circuit from terminal to terminal. When, however, either lamp is put in the socket, it will press up the push m' , and thus lift one of the springs off the plate v' , and thus divert the current through the carbon of the lamp, as will be seen by tracing the connections in Fig. 7—that is, if the lamp on the left is inserted the current will flow from terminal $+$ by spring n' , plate v' , and wire 3 to the lamp-socket and the lamp, and from the lamp by push $m' m'$ and spring n' to terminal $-$. If the lamp on the right is inserted, it will be seen that only one will be lighted, as both springs n' will then leave the plate v' , and thus compel the current to pass through one lamp only. Now I mount the turn-table n of the disruptive cut-out over the plate v' on the spindle m^2 , which passes down through the plate v' and through the middle of the holder v , and terminates with a small manipulating knob j , midway between the lamp-sockets. The disruptible insulator s is held on the under side of the table n , and is pressed upon by the two springs $u u$, extending from the terminals $+$ $-$. It will therefore be seen by following the connections that if both lamps are inserted the one on the right will be lighted; but if this should become broken the current will then jump through the insulator s from the spring u on the right to the table n , and flow thence by spindle m^2 , plate v' , and wire 3 to the lamp on the left, and thence by push m' and spring n' of said lamp to the opposite terminal $-$, thus instantaneously lighting the lamp on the left. If both lamps should break, a short circuit would be made between the terminals directly through both springs $u u$ and the table n by the disrupting action at both springs, as will be readily understood on reference to Fig. 7. By turning the knob j the perforated or disrupted spots on the insulator may be removed from the springs and a perfect part of the insulator brought under the same for continued action, as will be understood. It will

be seen that if the lamp in Fig. 7 is removed from its socket the retreat of the push m' will lower the contact-spring n' on the plate v' , and thus form a short circuit from terminal to terminal, with the same effect as is the case with the contacts $n o$ in Fig. 2, while the springs $u u$, insulator s , and table n of course actually correspond to the same elements in Fig. 2.

Referring to Figs. 1 and 2, it will be noted that the casing d is held firmly in position about the internal parts of the holder by encircling at one end the rim c on the head b and abutting against the shoulder on said rim, while the other or narrow end of the casing encircles the hard-rubber nut a' , which is screwed over the socket a and has a shoudered rim, which abuts against the narrow end of the casing, as well shown in Figs. 1 and 2. It will therefore be seen that the rubber nut a' insulates the external casing from the conducting-socket of the holder, while the slate plate e insulates both the head b and the casing from the other conducting parts of the holder, so that no shock can therefore be received from the casing. To reduce the possibility of this shock further, I make the casing d of sheet metal, (preferably iron,) which is completely coated with a vitreous enamel—such, for example, as that used on "granite ware," which I find makes a perfect electric insulator, and is at the same time fire-proof, imparts a handsome appearance to the holder, and is quite inexpensive, and thus forms a very advantageous feature of my holder. Other vitreous enamels may be substituted, and the coating of enamel may be of any desired thickness.

What I claim as my invention is—

1. In an electric-lamp holder, the movable terminal push m and contact n , connected thereto, with a contact o of opposite polarity on which it normally seats, substantially as shown and described.

2. In a lamp-holder, the combination, with the fixed socket a , forming one polar terminal, and the movable push m' , forming the other terminal, of a contact n attached to said latter terminal, a seating contact o of opposite polarity, and a spring tending constantly to close said contacts $n o$, substantially as and for the purpose set forth.

3. In a holder for electric lamps, the combination, with the movable conducting-push m' , adapted to contact with one terminal of the lamp when inserted in its socket, of the plate n , attached to said push m' and having one polarity, with a thin disruptible insulator s on said plate, and a contact-spring u , resting on said insulator and connected with the terminal of opposite polarity, substantially as and for the purpose set forth.

4. In a holder for incandescent electric lamps, the combination, to form a disruptive cut-out, of a rotary conducting-table connected to one terminal, a thin disruptible insulating layer or disk thereon, and a contact-

tongue bearing on the opposite side of said disk and connected to the opposite terminal, substantially as set forth.

5. In a disruptive cut-out, the combination, with the rotary table *n*, axial spindle *m*, and bearing *l'*, of the disruptible insulator *s* and contact-spring *u*, arranged and operating substantially as shown and described.

6. In an electric-lamp holder adapted for serial circuits, the combination, with a hand-switch arranged, when closed, to form a short circuit between the terminals, of a spring tending constantly to open said switch, whereby when said switch is released it opens instantaneously, substantially as and for the purpose set forth.

7. In an electric-lamp holder adapted for serial circuits, a movable contact-maker arranged in the receiving-socket for the lamp and in the path of the lamp, so arranged that when the lamp is inserted the contact is opened, and vice versa, with a distinct hand-switch arranged, when closed, to short-circuit or cut out the lamp and said contact-maker, with a spring tending constantly to open said switch, whereby when the switch is released the short circuit is broken instantly and the lamp switched in without danger of arcing at the movable contact-maker, substantially as herein set forth.

8. In an electric-lamp holder, the combination, with a hand-switch arranged, when closed, to short-circuit or cut off the lamp, of a spring tending constantly to open said switch instantaneously, and a catch to hold said switch closed until designedly released, substantially as and for the purpose set forth.

9. In an electric-lamp holder, the combination, with the insulating-base *e*, of the ring *h* and legs *k* *k'*, with the bracket *l*, socket *a*, push *m'*, spindle *m*, contact *n*, and contact *o*, substantially as shown and described.

10. The combination, with the head *b* and insulating-plate *e*, secured thereto, of the ring *h*, secured to the plate, socket *a*, secured to the ring, external casing *d*, and insulating-nut *a'*, arranged substantially as shown and described.

11. In a disruptive cut-out, the combination, with a rotary conducting-table *n*, disruptible insulator thereon, and contact-tongue bearing upon the same, of an axial spindle extending from said table, a bearing supporting the same, and an operating-head on the end of said spindle, substantially as shown and described.
